UNITED STATES PATENT OFFICE.

JACOB EDSON, OF BOSTON, ASSIGNOR OF ONE-HALF TO JOHN S. RICE, OF CAMBRIDGEPORT, MASSACHUSETTS.

PEN CLEANER AND HOLDER.

SPECIFICATION forming part of Letters Patent No. 380,650, dated April 3, 1888.

Application filed January 16, 1888. Serial No. 260,821. (No model.)

To all whom it may concern:

Be it known that I, JACOB EDSON, a citizen of the United States, and a resident of Boston, in the county of Suffolk and State of Massachusetts, have invented new and useful Improvements in Pen Cleaners and Holders, of which the following, taken in connection with the accompanying drawings, is a specification.

This invention relates to improvements in pen cleaner and holder and paper-weight combined, and it is carried out as follows, reference being had to the accompanying drawings, where—

Figure 1 represents a plan view of the invention. Fig. 2 represents a front elevation, shown partly in section. Fig. 3 represents an end view; and Fig. 4 represents a cross-section on the broken line A B, shown in Fig. 1.

Similar letters refer to similar parts wherever they occur on the different parts of the drawings.

a is the block, composed of a series of vertical sheets of paper or other suitable fibrous or textile material, which sheets are laid side by side and preferably inclosed by means of a suitable binding-strip, b, as is common in devices of this kind. Said block is reversible, so that after its upper end has been used for the purpose of holding and cleaning pens 30 it may be reversed and its opposite side used for the same purpose.

The paper block a is inserted and adapted to rest in the base or socket c, that is preferably made of cast metal, glass, or other heavy material, so that the device may serve as a paper-weight in addition to its use as a pen cleaner and holder. The socket or base c is made of increased size at its bottom, to give it great stability, and curved or tapering toward its upper end, as shown in the drawings, to make it light in such upper end, and when so made if no other devices were added it would be difficult to take hold of it and lift it whenever its position on the writing-table 45 was to be changed. To obviate this difficulty, I make on two of its opposite sides the finger projections c' c', as shown, which will enable the operator to take hold of the base or socket c, whenever so desired, to change its position 50 on the table or other piece of furniture where it is used.

For the purpose of preventing the lower corners of the block a from being crushed or injured when inserted in the base or socket

c, I make in the bottom of the latter a circumferential groove, c'', as shown in Figs. 2 and 4 and in dotted lines in Figs. 1 and 3, which will permit the block a to be inserted in the base c without causing injury to the lower corner edges of said block a and allowing the middle portion of said block to rest on the central raised portion, c³, in the bottom of said frame c, as shown in Figs. 2 and 4. It is also essential that the block a shall be capable of being quickly reversed in its position within the base or socket c, and for this purpose I make on two opposite sides or ends of the latter the cut-away portions c⁴ c⁴, of suitable size or shape, by which arrangement the sides or ends of the block a are partially exposed, to enable the operator to insert his or her fingers in such cut-away portions and thus grasp the block a from two opposite sides or ends to permit of its removal or reversion, as the case may be.

Having thus fully described the nature, construction, and operation of my invention, I wish to secure by Letters Patent, and claim—

1. The reversible block a, in combination with the base or socket c, having tapering or curved sides and ends, as described, and having on two opposite sides the finger projections c' c', as and for the purpose set forth.

2. The reversible block a, in combination with the base or socket c, having on two opposite sides or ends the cut-away portions c⁴ c⁴, as and for the purpose set forth.

3. The reversible block a, in combination with the base or socket c, having its bottom provided with the circumferential groove c'', and central raised portion, c³, as and for the purpose set forth.

4. The reversible block a, in combination with the base or socket c, having tapering or curved sides, as described, and having on two of its opposite sides or ends the finger projections or lifters c' c', the cut-away portions c⁴ c⁴, and having in its bottom the circumferential groove c'', substantially as and for the purpose set forth.

In testimony whereof I have signed my name to this specification, in the presence of two subscribing witnesses, on this 14th day of January, A. D. 1888.

JACOB EDSON.

Witnesses:

ALBAN ANDRÉN,
HENRY CHADBURN.
